Primary Examiner — Susan E Krakower*Assistant Examiner* — Jerry Shiuan-Hua Hsu(57) **CLAIM**

The ornamental design for a vehicle fender, as shown and described.

DESCRIPTION

FIG. 1 is a front and left perspective view of the vehicle fender according to the present disclosure. The mirror image of the vehicle fender is claimed but not shown;

FIG. 2 is a top plan view thereof;

FIG. 3 is a left end elevation view thereof; and,

FIG. 4 is a front elevation view thereof.

The broken lines shown in the drawings depict portions of the vehicle fender that form no part of the claimed design.
